(57) **CLAIM**

The ornamental design for a load control with sensor and removable front panel, as shown and described.

DESCRIPTION

FIG. 1 is a front left perspective view illustrating our new design for a load control with sensor and removable front panel with the broken lines showing, for illustrative purposes only, connectors on a back side of the removable front panel, a strap for mounting the sensor to a surface and a housing that are not part of the claimed design;

FIG. 2 is a front view thereof with the broken lines showing the strap;

FIG. 3 is a back view thereof with the broken lines showing the strap and the housing;

FIG. 4 is left side view thereof with the broken lines showing the strap and the housing;

FIG. 5 is a right side view thereof with the broken lines showing the strap and the housing;

FIG. 6 is a top view thereof with the broken lines showing the connectors, the strap and the housing;

FIG. 7 is a bottom view thereof with the broken lines showing the strap and the housing;

FIG. 8 a front left perspective view illustrating the removable front panel shown separately to depict features not visible in the other views with the broken lines showing the connectors;

FIG. 9 is a front view of the removable front panel with the broken lines showing the connectors;

FIG. 10 is a back view thereof with the broken lines showing the connectors;

FIG. 11 is left side view thereof with the broken lines showing the connectors;

FIG. 12 is a right side view thereof with the broken lines showing the connectors;

FIG. 13 is a top view thereof with the broken lines showing the connectors; and,

FIG. 14 is a bottom view thereof with the broken lines showing the connectors.

The broken lines shown are for illustrative purposes only and form no part of the claimed design.

1 Claim, 6 Drawing Sheets
